(57) **CLAIM**

The ornamental design for mixing faucet, as shown and described.

DESCRIPTION

FIG. 1 is a perspective view of the mixing faucet showing a new ornamental design thereof;

FIG. 2 is a front elevation view of the mixing faucet shown in FIG. 1;

FIG. 3 is a rear elevation view of the mixing faucet shown in FIG. 1;

FIG. 4 is a right side elevation view of the mixing faucet shown in FIG. 1;

FIG. 5 is a left side elevation view of the mixing faucet shown in FIG. 1;

FIG. 6 is a top plan view of the mixing faucet shown in FIG. 1; and,

FIG. 7 is a bottom plan view of the mixing faucet shown in FIG. 1.

The broken lines are included for the purpose of illustrating a portion of the mixing faucet that forms no part of the claimed design.

1 Claim, 3 Drawing Sheets
